UNITED STATES PATENT OFFICE.

VALLEY M. KIEFFER, OF BUFFALO, NEW YORK.

DESIGN FOR A DOLL.

Application filed December 22, 1921. Serial No. 524,314. Term of patent 3½ years.

To all whom it may concern:

Be it known that I, VALLEY M. KIEFFER, a citizen of the United States, residing at Buffalo, in the county of Erie and State of New York, have invented a new, original, and ornamental Design for Dolls, of which the following is a specification, reference being had to the accompanying drawing, forming part thereof, wherein—

I claim:

The ornamental design for a doll, as shown.

In testimony whereof, I affix my signature.

VALLEY M. KIEFFER.
